UNITED STATES PATENT OFFICE.

WILHELM GROENEBAUM, OF NEU-BABELSBERG, NEAR BERLIN, GERMANY, ASSIGNOR
TO THE FIRM TELEGRAPHON AKTIENGESELLSCHAFT, OF BERLIN, GERMANY.

TELEPHONICALLY-OPERATED RECORDING TALKING MACHINE.

Application filed October 17, 1924. Serial No. 744,169.

To all whom it may concern:

Be it known that I, WILHELM GROENEBAUM, a citizen of Germany, residing at Neu-Babelsberg, near Berlin, Germany, have invented certain new and useful Improvements in Telephonically-Operated Recording Talking Machines, of which the following is a specification.

This invention relates to apparatus for recording by telephone upon the record surface of a talking machine; and it comprises chiefly a system which permits any one of several speaking lines to be put into connection with the recorder of the talking machine by operation of a switch controlling the respective line, while at the same time the other lines are excluded from such connection.

The accompanying drawing shows one embodiment of the invention, in which microphones belonging to several stations can one at a time be brought into connection as desired with the telephonic recording device of a talking machine which may, for instance, be placed in a separate room. The drawing embodies a diagram of connections for such an installation. The drawing is divided into three parts by the lines I—I and II—II; the upper part contains the apparatus and accessories which constitute the recording station; the middle and lower parts show each the apparatus and accessories at a station *a* and *b* respectively, of which stations there may be any desired number similarly equipped.

The instrument for receiving what is dictated into the microphone comprises a cylinder *A* driven by the motor *B*, for instance through a belt *C*. The recorder *D* inscribes what is said upon the surface of the cylinder as it is moved along the cylinder by a threaded spindle *E*, driven through a pair of gear wheels *F*. At the end of its movement towards the right the recorder *D* abuts on one member of a contact *U* and breaks the contact. Associated with the talking machine are also a relay *G* with contact springs 1, 2, 3, 4; batteries *K*¹ and *K*²; an engaged signal *M* and a supervisory signal *N*. The apparatus at each speaking station includes a relay *O* with contact springs 1—8, an actuating switch *P* with contact springs 1—5, an interrupting switch *Q*, a microphone *R*, an engaged signal *S* and a supervisory signal *T*.

If a person at station *a*, for instance, desires to dictate to the recorder, switch *P* is depressed. The following circuit (1) is then established: from positive of battery *K*¹, conductor 1, contact springs 3, 2 of *P*, conductor 7, and thence over the engaged signal *M* on the one hand and over the two engaged signals *S* on the other hand, to conductor 2 and so to the negative pole of battery *K*¹.

The signals *M* and *S* therefore show at the recording station, at the station which is dictating, and at all other speaking stations, that the recording station is busy.

Depression of the switch *P* at station *a* also brings contact springs 4 and 5 into contact, so that the following circuit (2) is completed: from positive of battery *K*¹, contact *U*, conductor 4, switch *Q*, contact springs 5, 4 of *P*, contact springs 6, 5 of relay *O*, conductor 3, winding of relay *G* to negative pole of *K*¹.

The relay *G* therefore responds and closes its contacts. Contacts 1, 2 of relay *G* complete the circuit of the motor *B* over the following path (3): from positive of *K*¹, through motor *B*, and contact springs 2, 1, to negative of *K*¹.

The contact of contact springs 3, 4 of relay *G* closes a circuit (4) for battery *K*²; from positive of *K*², through recorder *D*, contact springs 4, 3, of relay *G*, conductor 5, microphone *R*, contact springs 4, 3 of relay *O*, and conductor 6 to negative pole of *K*².

When the microphone *R* at station *a* is spoken into, oscillating currents are superimposed upon the current flowing through the circuit (4) and these actuate the recorder *D* which inscribes what is said upon the cylinder *A*.

As above stated circuit (2) contains the switch *Q* of station *a*. When this switch is opened therefore, relay *G* ceases to be excited, and disconnects the motor *B*, at its contact 1, 2; consequently the motor stops. The microphone circuit is interrupted at contact 3, 4 of relay *G*, but the circuits which depend on the contact 2, 3 of switch *P* remain unchanged. Switch *Q* is intended to be opened during a pause in dictation, so as to economize battery current, and also economize space on the recorder.

Circuit (2) above described has the following two branches: (5) conductor 3, su-

pervisory signal N, conductor 2 to negative of K¹; (6) contact springs 6, 7, 8 of relay O, supervisory relay T, to negative of K¹.

The two supervisory relays N and T thus 5 show that relay G has responded and that the end contact U is closed.

To prevent the dictation of station a being interrupted by the second or any other station is the function in the first place of 10 the engaged signals S which are provided at all the stations and are connected in parallel between the conductors 7 and 2, so that they appear simultaneously. In addition depression of switch P at station a establishes the following branch (7) from circuit 15 (1) described above; conductor 7, contact springs 2, 1 of all undepressed switches P at the second, third, and other stations, windings of the corresponding relays O, conductor 20 2 to negative pole of battery K¹.

The relays O of the second, third, and other stations such as b therefore attract their armatures. Contact between springs 1, 25 2 of a relay O bridges the contact springs 1, 3 of the corresponding switch P, so that the excitation of the relay O cannot be interrupted by depression of this switch. Also contact between springs 3 and 4, 5 and 6, and 7 and 8, of relay O is broken as the result 30 of its excitation, so that the circuits (2), (4) and (6) which as described above for station a include the corresponding contacts of the relay O of that station cannot be established.

35 In place of a microphone B designed only for dictation upon cylinder A, the several speaking stations may be equipped with a complete telephone apparatus for telephone conversations the microphone of the apparatus being connected in the manner described to the recorder D for recording the conversation. There may be a separate line to each station for telephone conversations; but all the stations can also be joined to a 45 common line through a line selector or through series connection.

What I claim is:—

1. A telephone installation comprising a 50 telephonically operated recording talking machine, a plurality of speaking stations each including a microphone, an electric circuit operatively connecting the microphones to the recorder of said machine, and means at each station for causing its microphone to be connected to the talking machine recorder and for preventing any second 55 microphone from being so connected.

2. A telephone installation comprising a 60 telephonically operated recording talking machine, an electric motor for operating the talking machine, an electric circuit operatively connecting the motor and recorder of said machine to a source of power, a relay adapted on excitation to complete 65 the circuit of said motor and the circuit

of the recorder of the talking machine, a plurality of speaking stations each including a microphone, means establishing a circuit between the microphones and said recorder, a switch at each station adapted to close the circuit of said relay and means operated by said switch for interrupting the microphone circuits of all other stations. 70

3. A telephone installation comprising a 75 telephonically operated recording talking machine, a plurality of speaking stations each including a microphone, means including a plurality of relays and a source of power for establishing an operative connection between the microphones and the recorder of said talking machine, a switch at each station, and means including said relays adapted to be operated by said switch for completing the circuit of the recorder and its own microphone, and for interrupting the circuit of all other microphones. 80

4. A telephone installation comprising a 85 telephonically operated recording talking machine, a plurality of speaking stations each including a microphone, means connecting said microphone with the recorder of the talking machine, a motor for operating the talking machine, a switch at each station, an engaged signal at each station, and means operated by said switches for 90 starting said motor and actuating all of said engaged signals.

5. A telephone installation comprising a 95 telephonically operated recording talking machine, a plurality of speaking stations each including a microphone, means for connecting said microphones with the recorder of the talking machine, a control circuit for said talking machine by the completion of which it is put in operation, a switch at each station adapted to complete said control circuit, a lock-out relay at each station, a contact at each station included in said control circuit and opened by the excitation of said lock-out relay, and a circuit 100 for said lock-out relay adapted to be completed by the switch of any station except its own. 110

6. In a telephone installation the combination of a telephonically operated recording 115 talking machine, a plurality of speaking stations each including a microphone, connections between said microphones and the recorder of said talking machine, a motor for driving the talking machine, a control device for starting the motor and closing the recorder circuit, a control circuit for actuating said device extending to all the stations, a lock-out device at each station adapted to interrupt said control circuit, a 120 switch at each station adapted to complete the control circuit at that station and to operate the lock-out device of all other stations, and an interrupting switch at each station adapted to interrupt said control circuit. 130

cuit and thereby stop the motor and break the microphone circuit without affecting said lock-out device.

7. A telephone installation comprising a telephonically operated recording talking machine, a motor for driving said talking machine, a relay adapted to close and open the circuits of the recorder and of said motor, a plurality of speaking stations each including a microphone, a control circuit for said relay extending to each station, a switch at each station adapted to complete said control circuit, a lock-out relay at each station adapted to break the control circuit at that station, and a circuit for each said lock-out relay including a contact broken by the actuation of the switch at the same station, a parallel contact completed by the excitation of the relay, and parallel contacts at other stations completed by actuation of the switches of said stations.

8. In a telephone installation comprising a telephonically operated recording talking machine and a plurality of stations each including a microphone adapted to be connected with the recorder of said talking machine, the combination with a switch at each station, of means actuated by each switch for setting said talking machine in operation, and for connecting said recorder in circuit with the microphone of that station, means at each station and adapted to be actuated by the switch of any other station for rendering its own switch inoperative, and additional means at each station for actuating said first-named means to stop the operation of said machine and to open the microphone recorder circuit.

9. A telephone installation comprising a telephonically operated recording talking machine, a plurality of speaking stations each including a microphone, a control device adapted to set said talking machine in operation, and to connect said microphones in circuit with the recorder of said machine, a control circuit for said device extending to each station, a switch at each station adapted to close said control circuit, and a supervisory circuit in parallel with a part of said control circuit and adapted to be closed by said switch.

10. A telephone installation comprising a telephonically operated recording talking machine, a plurality of speaking stations each including a microphone, a control device adapted to set said talking machine in operation for recording, a control circuit for

said device extending to each station, a switch at each station adapted to close said control circuit, a supervisory circuit in parallel with a part of said control circuit and adapted to be closed by said switch, and a contact in said supervisory circuit adapted to be broken by the recorder of said talking machine on reaching the end of its traverse.

11. A telephone installation comprising a telephonically operated recording talking machine, a plurality of speaking stations each including a microphone, means for connecting all of said microphones in parallel with the recorder of said talking machine, and means at each speaking station for completing the circuit through the recorder and the microphone of that station, and for breaking the microphone circuit of every other station.

12. A telephone installation comprising a telephonically operated recording talking machine, a plurality of speaking stations each including a microphone, connections between said microphones and the recorder of said talking machine, a lock-out relay at each station adapted on excitation to interrupt the connections of its microphone, a switch at each station, and an exciting circuit for said lock-out relay comprising a contact broken by the actuation of its own switch, a parallel contact completed by the excitation of the relay, and a plurality of contacts one at each station in parallel with each other and each adapted to be completed by the actuation of the switch of the respective station.

13. A telephone installation comprising a telephonically operated recording talking machine, a plurality of speaking stations each including a microphone, connections between said microphones and the recorder of said talking machine, a lock-out relay at each station adapted on excitation to interrupt the connections of its microphone, a switch at each station, an exciting circuit for said lock-out relay comprising a contact broken by the actuation of its own switch, a parallel contact completed by the excitation of the relay, a plurality of contacts one at each station in parallel with each other and each adapted to be completed by the actuation of the switch of the respective station, and an engaged signal at each station bridged across said lock-out relay and the parallel contacts at the same station.

In testimony whereof I affix my signature.
WILHELM GROENEBAUM.
